BALL POINT PEN

Charles K. Lovejoy, Atlanta, Ga., assignor to Scripto,
Inc., a corporation of Georgia

Filed Apr. 14, 1959, Ser. No. 55,493

Term of patent 14 years

(Cl. D74—17)

Fig. 1 Fig. 2 Fig. 3

Fig. 4 Fig. 5 Fig. 6

Fig. 1 is a front elevational view of a ball point pen embodying my new design;

Fig. 2 is a side elevational view thereof;

Fig. 3 is a rear elevational view;

Fig. 4 is a horizontal sectional view taken along line 4—4 of Fig. 1 the details of the interior construction of the pen having been omitted;

Fig. 5 is a horizontal sectional view taken along line 5—5 of Fig. 1; and

Fig. 6 is a horizontal sectional view taken along line 6—6 of Fig. 1.

The essential features of my design reside in the portions shown in solid lines on the drawing.

I claim:

The ornamental design for a ball point pen, as shown and described.
